UNITED STATES PATENT OFFICE

JAMES O. DAVIS, OF WABASH, INDIANA, ASSIGNOR TO MINNEAPOLIS-HONEYWELL
REGULATOR COMPANY, OF WABASH, INDIANA, A CORPORATION OF DELAWARE

SAFETY CONTROL FOR BURNER MOTORS

Application filed September 12, 1930. Serial No. 481,579.

The present application relates to safety control mechanism for oil burner installations, and among the object of the invention are to provide such a control which will be 5 relatively simple in construction, which will provide for thermostatic control of the burner mechanism, which includes mechanism of such character as to prevent a supply of fuel to the burner in case of failure of ignition, 10 and to cut off the supply of fuel to the burner in case of failure of combustion, and which is so constructed as to provide for snap actuation of all metal to metal contact switches both in the making of contact and in the 15 breaking thereof. The present invention provides novel means for operating switches of the metal to metal contact type, and I consider this means to be broadly new. Further objects of the invention will appear as 20 the description proceeds.

To the accomplishment of the above and related objects, my invention may be embodied in the form illustrated in the accompanying drawing, attention being called to 25 the fact, however, that the drawing is illustrative only and that change may be made in the specific construction illustrated and described, so long as the scope of the appended claims is not violated.

30 In the accompanying drawing,

Fig. 1 is a diagrammatic view of mechanism constructed in accordance with my invention;

Fig. 2 is a section through the control 35 housing; and

Fig. 3 is a side elevation of the control housing, a portion thereof being broken away to disclose the control elements housed therein.

40 Referring more particularly to the drawing, it will be seen that the disclosed mechanism comprises a shaft 10 adapted to be driven by motor 11 and carrying the brush arm 12 of a maintaining switch 13. Said shaft 45 further carries a plurality of cams 14, 15, 16, 17, 18, 19, 20, 21, 22 and 23, said cams being adapted, respectively, to actuate a series 50 of contact fingers later to be described. The installation includes also a thermostat 60, a stack switch 95, an ignition coil 76, an oil

supplying pump 84 (for which may be substituted an electrically operated valve in a gravity system), an air blower 90, and an oil burner (not shown).

The maintaining switch 13 comprises a 55 plurality of annular, or part-annular, concentric tracks 47, 49 and 55 with which co-operate, respectively, brushes 48, 50 and 56 carried on the arm 12. The maintaining switch also comprises two diametrically 60 spaced contact buttons 53 and 54 adapted to be contacted by the brush 50.

A choke transformer comprising a primary coil 67 and a secondary coil 69 has its primary connected in series in the circuit of 65 the motor 11, this transformer being so proportioned that no current will flow through the primary coil even though the circuit of said coil is closed, unless the secondary coil circuit is closed.

70 It is, of course, in any oil burner control, desirable that, under certain conditions, the control should attain a "locked-up" condition of such character that neither the burner nor the control can be operated after the control 75 has entered such condition without receiving the attention of the operator. The present control is illustrated in Fig. 1 in such a locked-up condition. In the illustrated positions of the parts, the secondary coil 69 of the 80 choke transformer is shorted through a circuit as follows:—wire 74, track 47, brush 48, arm 12, brush 50, track 49, wire 71, wire 70, and coil 69. A finger 40 has its upper end pivoted in the control casing 120, and the 85 free end of said finger is aligned for cooperation with the cam 22. A second finger 42 is similarly mounted closely adjacent the finger 40, the free end of said finger 42 being 90 positioned for actuation by the cam 23. The finger 40 carries a contact button 41 adapted, in certain positions of said fingers 40 and 42, to contact a contact button 43 carried by the finger 42. The finger 42 has mounted thereon an arm 44 which, at its free end, carries a contact button 45 adapted, in certain other positions of the fingers 40 and 42, to engage a contact button 46 likewise carried by the finger 40. In the illustrated positions of the 95 parts, the contact buttons 41 and 43 are en- 100

- gaged while the contact buttons 45 and 46 are separated. As will be readily seen, the separation of the contact buttons 45 and 46 prevents the making of a circuit through the primary coil 67 of the choke transformer for energizing the motor 11 so that, in the illustrated condition, the control is holding not only the burner, but also itself, in inactive condition.
- 10 Fingers 24 and 26 are pivoted with their free ends in cooperative relation with the cams 14 and 15 respectively, and the finger 24 carries a contact button 25 adapted, in certain positions of said fingers, to engage a contact point 27 carried by the finger 26. Similarly, fingers 28 and 30 are positioned to be actuated by cams 16 and 17 and carry cooperative contact points 29 and 31; fingers 32 and 34 are positioned to be actuated by cams 18 and 19 respectively and carry contact buttons 33 and 35; and fingers 36 and 38 are positioned to be actuated by cams 20 and 21 and carry contact buttons 37 and 39. All of the fingers are provided with spring means urging the free ends of said fingers toward contact with their respective cams. In Fig. 2, I have illustrated coil springs 122 surrounding the pivots of the fingers, one end of each spring engaging its finger and the other end thereof engaging an abutment on the carrying piece 121 upon which said fingers are mounted, but it is to be understood that any spring means having this function may be substituted for those illustrated.
- 15 25 Means is provided for reinitiating the operation of the control after the same has reached the locked-up condition illustrated in Fig. 1. A contact bar 86 is provided with a push button 100, and is normally urged into the position illustrated by an expansion spring 106 or the like. If the bar 86 is moved, by pressing upon the button 100, into contact with the terminals of the wires 102 and 103, an energizing circuit for the motor 11 is established as follows:—power line 57, wire 63, wire 101, wire 102, bar 86, wire 103, wire 78, finger 42, contact button 43, contact button 41, finger 40, wire 65, motor 11, wire 66, primary coil 67, wire 68, and power line 58. Since the secondary coil 69 of the choke transformer is already energized through the circuit above described, the establishment of this circuit initiates clockwise rotation of the motor 11 as viewed from the left end of Fig. 1. Almost immediately upon initiation of such rotation, the finger 42 drops off the shoulder 105 of its cam 23, and the brush 50 moves into contact with the button 54.
- 20 It is to be noted that this movement of the finger 42 which, of course, breaks the contact between the buttons 41 and 43, is an abrupt one and is effected by the spring 122, the free end of the finger 42 dropping precipitately from the apex of the radial shoulder 105. This movement not only breaks the motor en-

in contact with the post 61, the control mechanism now comes to rest with no operative circuits established. As illustrated, however, the arm 59 is in contact with the post 61, as is always the case when the thermostat is calling for heat, and consequently a new secondary circuit is established as follows:—wire 70, wire 71, track 49, wire 72, thermostat post 60, thermostat arm 59, thermostat post 61, wire 73, button 53, brush 50, arm 12, brush 48, track 47, wire 74, and secondary coil 69. The motor 11 and primary coil 67 being energized through the previously described circuit through the contacts 45 and 46, the motor continues the rotation of the shaft 10 and moves the brush 50 off the button 53 and onto the track 49, thus destroying the control of the thermostat and again energizing or shorting the secondary 69 through the previously described circuit including the brush 50 and the track 49.

As the brush 50 leaves the button 53, the finger 32 drops off the shoulder 109 of its cam 18, thus establishing contact between the points 33 and 35 and establishing an ignition circuit as follows:—power line 57, wire 63, finger 36, contact button 37, button 39, finger 38, wire 77, wire 78, wire 79, finger 34, contact 35, contact 33, finger 32, wire 80, ignition coil 76, wire 81, wire 68, and power line 58. Almost immediately thereafter, as the motor 11 continues to rotate, the fingers 24 and 28 drop off the shoulders 110 and 111 of their respective cams 14 and 16, thus establishing contact between the buttons 25 and 27 and between the buttons 29 and 31. Closure of these switches establishes a circuit through the oil control 84 as follows:—power line 57, wire 63, finger 36, contact 37, contact 39, finger 38, wire 77, wire 78, wire 82, finger 26, contact 27, contact 25, finger 24, wire 83, oil control 84, wire 85, bar 86, wire 87, wire 81, wire 68, and power line 58; and a circuit through the blower motor as follows:—power line 57, wire 63, finger 36, contact 37, contact 39, finger 38, wire 77, wire 78, wire 88, finger 30, contact 31, contact 29, finger 28, wire 89, blower motor 90, wire 91, wire 85, bar 86, wire 87, wire 81, wire 68, and power line 58.

Conditions are now proper for the initiation of combustion, and the motor 11 continues to rotate, holding these favorable conditions for a short time, or until a position substantially that shown in Fig. 1 is reached. Just before this position is reached, the fingers 34, 38 and 40 drop off the shoulders 112, 113 and 114 of their respective cams 19, 21 and 22; whereby the primary energizing circuit for the motor 11 is broken at 45—46; the ignition circuit is broken at 37—39 and at 33—35; and the temporary energizing circuits for the oil control 84 and the blower motor 90 are broken at 37—39. If ignition has not taken place by this time, the motor

stops in the locked-up position shown in the drawing.

If, however, ignition has taken place before the fingers drop off the shoulders as above described, the stack thermostat element 95 will have been swung into position to establish electrical contact between the terminals of the mercury tube 99, and maintaining circuits through the oil control 84 and the blower motor 90 will have been established as follows:—power line 57, wire 63, wire 101, tube 99, wire 78, wire 82, finger 26, contact 27, contact 25, finger 24, wire 83, oil control 84, wire 85, bar 86, wire 87, wire 81, wire 68, and power line 58; and power line 57, wire 63, wire 101, mercury tube 99, wire 78, wire 88, finger 30, contact 31, contact 29, finger 28, wire 89, blower motor 90, wire 91, wire 85, bar 86, wire 87, wire 81, wire 68, and power line 58 to continue the supply of fuel to the burner.

A primary motor circuit is likewise maintained through tube 99 as follows:—power line 57, wire 63, wire 101, tube 99, wire 78, finger 42, contact 43, contact 41, finger 40, wire 65, motor 11, wire 66, primary 67, wire 68, and power line 58. Since there is, at this time, a secondary circuit through the secondary coil 69 of the choke transformer as follows:—wire 70, wire 71, track 49, brush 50, arm 12, brush 48, track 47, wire 74, and secondary coil 69, the motor 11 will continue to operate until the brush 50 reaches the button 54. Since the stack thermostat 95 has been swung to its hot position, there is no closed circuit through the secondary coil 69 in this position of the parts, and the motor will stop. This is the normal operating condition of the control.

If, for any reason, the flame should be accidentally extinguished at this time, the stack thermostat would quickly cool down sufficiently to cause the element 95 to swing into the position illustrated, whereby the secondary coil 69 would be shorted as follows:—70—96—94—93—55—56—12—48—47—74—69, and the device will be recycled in the manner above described, coming finally either to a normal operating condition or to a locked-up condition depending upon whether or not combustion is initiated, as explained above.

Assuming that the burner operates properly until the temperature of the controlled space reaches the predetermined optimum, the room thermostat will be shifted to call for cold, the arm 59 thereof moving into contact with the post 62. It being remembered that a closed primary motor circuit already exists, it will be seen that this shift of the arm 59 will initiate operation of the control motor 11 by shorting the secondary coil 69 as follows:—wire 70, wire 71, track 49, wire 72, post 60, arm 59, post 62, wire 104, button 54, brush 50, arm 12, brush 48, track 130

- 47, wire 74, and secondary coil 69. As the motor operates, the brush 50 is moved off the button 54 and onto the track 49, thus breaking the above described secondary circuit 5 and establishing another as previously traced, thus:—70—71—49—50—12—48—47—74—69 to continue the operation of the motor. As the brush 50 moves off the end 75 of the track 49, fingers 26 and 30 drop off the shoulders 10 107 and 108 of their respective cams 15 and 17, thus breaking the fuel-supplying circuits. As previously explained, the primary motor circuit is now through the contacts 45 and 46 and not through the contacts 43 and 41. 15 When the brush 50 leaves the track 49, it breaks the only secondary circuit, and the control motor stops, leaving only contacts 45 and 46 closed.

When the stack cools off sufficiently to 20 permit the element 95 to swing back to the position illustrated in the drawing the fluid in the tube 94 will short the terminals thereof, establishing a secondary motor circuit as follows:—70—96—94—93—55—56—12—25 48—47—74—69, and the motor will be operated through that circuit until the brush 56 leaves the track 55. Before that brush leaves its track, however, the brush 50 has re-engaged the track 49 at the end 97, to re-establish 30 the circuit 70—71—49—50—12—48—47—74—69, so that the motor will continue to operate until the brush 50 again rests on the button 53. In this position, the motor 11 35 will stop with contacts 25—27, 29—31, 33—35, and 41—43 open; and with contacts 37—39 and 45—46 closed, awaiting another call for heat by the room thermostat.

It will be noted that each movement of 40 any one of the several fingers which either establishes or breaks a circuit is a sudden one effected by the springs acting on said fingers. For instance, the contacts 25 and 27 are separated when the cam 15, which has flexed the 45 spring controlling the finger 26, moves to permit the free end of said finger to drop off the shoulder 107. As the cams 14 and 15 continue to rotate, the spring controlling the finger 24 is flexed, then the spring controlling 50 the finger 26 is again flexed, and thereafter the cam 14 moves to permit the free end of the finger 24 to drop off of the shoulder 110 of said cam under the influence of the spring 122, to establish contact between the buttons 55 25 and 27.

Thus, with one exception, each relative movement between the fingers of any pair occurs as the result of the controlling cam 60 for one of said fingers permitting its finger to drop off a precipitate shoulder, and this is true whether the movement effects separation or contact of the buttons carried by said fingers. The one exception mentioned is in the movement whereby the buttons 37 and 39 are 65 brought into contact, it being noted that the

cam 20 is truly circular, and that the cam 21 brings the finger 38 gradually into position to effect contact between the buttons 37 and 39. It will be noted that the buttons 37 and 39 are never brought into contact at a time 70 when such contact will close a circuit. That is, when the button 39 is brought into contact with the button 37, the contact buttons on the arms 24, 26, 28, 30, 32 and 34 are separated, as are the contact buttons 41 and 43, and the 75 wiring is such that no complete circuit can be traced through the buttons 37 and 39, under such conditions, it being noted that the buttons 37 and 39 are connected in parallel with the primary motor circuit through the 80 buttons 45 and 46.

I claim as my invention:

1. Switch mechanism comprising a finger, a second finger mounted for cooperation with said first finger and adapted to contact one 85 face thereof, resilient means biasing said fingers against movement in one direction, a contact member movable with, but insulated from, said second finger and adapted to contact the opposite face of said first finger, and means for flexing said resilient means and permitting said first finger to drop, under the influence of said resilient means, into contact with said second finger, and permitting said second finger to drop, under the influence of 90 said resilient means, to break the contact between said first finger and said second finger and to make contact between said contact member and said first finger.

2. Switch mechanism comprising a finger, a second finger mounted for cooperation with said first finger and adapted to contact one 95 face thereof, resilient means biasing said fingers against movement in one direction, a contact member movable with, but insulated from, said second finger and adapted to contact the opposite face of said first finger, a 100 shaft, a cam fast on said shaft and engaging said first finger, a second cam fast on said shaft and engaging said second finger, and means for rotating said shaft, said first cam being formed with a portion concentric with 105 said shaft on a radius such as to move said first finger against its bias, and with a portion of materially less radius, said portions being 110 separated by an abrupt shoulder, and said second cam being formed with a portion concentric with said shaft on a radius such as to move said second finger against its bias and substantially coextensive with said first-mentioned portion of said first cam, and with a portion of materially less radius, said portions of 115 said second cam being separated by an abrupt shoulder, peripherally spaced from the shoulder of said first cam.

3. Switch mechanism comprising a finger, a second finger mounted for cooperation with said first finger and adapted to contact one 120 face thereof, a contact member associated with, but insulated from, said second finger 125

and adapted to contact the opposite face of said first finger, said fingers and said member being resiliently biased against movement in one direction, operating means associated with said first finger, and operating means associated with said second finger, said means being operable to effect abrupt making and breaking of contact between said first finger and said second finger and between said first

10 finger and said contact member.

4. Switch mechanism comprising a finger, a second finger mounted for cooperation with said first finger and adapted to contact one face thereof, a contact member associated with, but insulated from, said second finger and adapted to contact the opposite face of said first finger, said fingers and said member being resiliently biased against movement in one direction, and means for moving said

15 fingers against the influence of their bias and subsequently permitting said first finger to move abruptly, under the influence of its bias, into contact with said second finger, and subsequently permitting said second finger to

20 move abruptly, under the influence of its bias to break such contact and to make contact between said first finger and said contact member.

In witness whereof, I have hereunto set my

30 hand at Wabash, Indiana, this 9th day of September, A. D. one thousand nine hundred and thirty.

JAMES O. DAVIS.
